UNITED STATES PATENT OFFICE.

EDMUND E. MORAND, OF WESTFIELD, MASSACHUSETTS.

CARBURETER.

1,172,031.

Specification of Letters Patent. Patented Feb. 15, 1916.

Application filed July 26, 1915. Serial No. 41,846.

To all whom it may concern:

Be it known that I, EDMUND E. MORAND, a citizen of the United States of America, and resident of Westfield, in the county of 5 Hampden and State of Massachusetts, have invented certain new and useful Improvements in Carbureters, of which the following is a full, clear, and exact description.

This invention relates to improvements in 10 carbureters for internal combustion engines, and one of the objects is to provide improved means for the actuation of the needle valve which more or less opens and closes the passage for the inflow of the gasoline into the 15 mixing chamber in conjunction with the intake of air into such chamber, the needle valve actuating means being operable for a vertical movement of the needle valve with certainty always on the line of its axis.

20 Another object of the invention is to provide improved means for the opening and closing of the shutter which controls the intake of air into the mixing chamber.

Another object is to provide an auxiliary 25 carbureter chamber with the necessary or desired provisions for the intake of fuel from the main carbureter liquid chamber and for the regulation of the air supplied thereinto so that even when the main carbureter is throttled or closed there may be, 30 independently thereof, a supply of vaporized fuel to the engine so that the latter need never be stalled but may run at a moderate speed or at a very low speed as desired; the provision of the supplemental carbureting means also rendering it possible to 35 obtain the additional capabilities for adjustments to employ carbureters more advantageously than usual in the use of carbureters as heretofore devised; and a further 40 object of the invention is to improve in the matter of details of construction the general construction of the device.

The invention is described in conjunction 45 with the accompanying drawings and is set forth in the claims.

In the drawings:—Figure 1 is a plan view of the carbureter; Fig. 2 is a front elevation of the same; Fig. 3 is a cross section taken 50 vertically and as seen on line 3—3, Fig. 1. Figs. 4 and 5 are horizontal cross sectional views representing the detailed construction of parts to be hereinafter referred to. Fig. 6 is a partial vertical cross section on 55 line 6—6, Fig. 1.

In the drawings, A represents the main liquid fuel chamber or float chamber of the

carbureter, the gasoline inlet to which entering at the rear side being not shown.

B represents a vertical chamber concentrically within the liquid chamber, and separated therefrom excepting as connection is made by the small transverse passage *a* and upstanding jet tube or nipple *b*. The chamber B by suitable provision and construction of casings is continued upwardly above the chambered body A, thereby providing in the upper portion B² of the centralized and the elongated chamber provision for the mixture of the gasoline or other liquid fuel 70 with the air. The upper end of the chamber B, B², is formed with a lateral opening *c* forming the port for a passage within the tubular extension C, for connection in the usual way with the cylinder or the manifold for a plurality of cylinders. At the front of the upper portion B² of the central chamber is an opening surrounded by a short annular hub *d*, such hub having a wall *d*² at its outer end or face provided with 80 apertures *d*³.

D represents a cup-shaped shutter having apertures *f* in its front wall to register with those in the aforementioned end wall *d*² and having its cylindrical flange-like portion *f*² 85 which fits about the annular hub or wall surrounding the air entrance opening into the mixing chamber a series of V-shaped teeth *g*. The cup-shaped and toothed shutter is retained on the spider-like front portion of 90 the upstanding casing in which the mixing chamber is inclosed by the screw *h* which forms the pivot for the shutter.

A cup-shaped cap closes the upper end of the central vertical chamber B², this cap 95 comprising the circular top plate E, and the tubular portion or elongated flange E² which fits down into the upstanding part of the mixing chamber casing. The said cap, seen to be of elongated cup-shape, is revolvable within the parts forming the support and bearing therefor for opening and throttling the carbureter, it having ports or apertures of considerable size in its depending annular portion. 100

The top E of the cap has the lever extension E³ by means of which the carbureter is operated; and the top E of the cap which is outwardly extended in the form of a flange to overhang the wall of the chamber B² is 110 provided with a series of V-shaped teeth *i* which are in mesh with the teeth *g* of the shutter D, so that when the cap E is revolvably moved to operate the carbureter to

more or less open or fully close the same, the shutter will be concurrently and proportionately moved.

In the central chamber between the cap E 5 and the jet tube b, is a centralized axially vertical hub F made as a central part of a spider. This hub has an axial bore there-through formed with a spline groove or slot j at one side.

10 G represents a block having opposite laterally extending members k k, preferably provided with knurled rollers k².

The block is provided with a depending sleeve m of comparatively small diameter, 15 but of considerable length, extended and guided down within the spider supported hub F, and is provided with a rib m² which is engaged in the slot groove or spline way j in the centralized hub-like part f.

15 H represents the needle valve, the tapered lower end of which coacts with the orifice at the upper end of the jet tube b. This needle valve is screw threaded centrally and vertically through the block G, and is extended 20 through and below the lower end of the sleeve m, and has a knurled head at its upper end for conveniently turning the needle valve for adjustment. The sleeve intermediate of its length is provided with a 25 shoulder forming enlargement m³ between which and the guiding bushing o the spiral spring p is applied in compression for exerting a downward, constant, force to the sleeve, the needle valve, and the block G, of 30 which latter the sleeve is an extension and through which the needle valve is screw threaded. The shoulder m³ of the sleeve being diametrically greater than the central opening in the bushing o which forms the 35 bearing for the sleeve, the bushing is made split on the plane of its axis, so that after 40 the block, sleeve, and needle valve have been brought to place in the carburetor in the relation shown in Fig. 3, the matched parts of 45 the two-part sleeve,—which is externally screw threaded,—may be screw engaged in the sufficiently large aperture therefor in the top member E of the cap.

15 L L represent a pair of arc shaped opposed concentrically arranged inclined cam plates formed of comparatively thin flat metal, each having its low end q fastened by rivets, or the equivalent, on the top E of the cap and having an adjusting screw r, engaged through its high end and bearing on the top of the cap.

The laterally extended roller provided members of the block G have impingements on, or rather they are impinged by the came 60 when the latter are moved under the revolute motion of the cap.

The needle valve H being properly adjusted in its thread engagement through the block and in its extension through the sleeve 65 continuation of the block relatively to the

orifice of the jet tube b will under the raising of the block by the opposing arc shaped cam plates, have its lifting movements always truly in the line of the axis of such needle valve—the described provisions being such 70 that there cannot be any degree of sidewise tilting or swinging of the valve. By turning both of the screws r the grade of the cam plates may be varied,—to be more or less steep,—for assuring under a given revolute movement of the cap the desired lifting and lowering of the needle valve. And as made clear through the engagements of the teeth i of the flanged top of the cap with the teeth g of the annular flanged portion of the 75 shutter D, the air ingress into the mixing chamber may always be proportioned to the ingress of the liquid or other fuel drawn into such chamber; and the apertures in the cap flange E² also correspondingly open and 80 close the outlet way through the engine connection member C or manifold.

Offset from and supported by the main float chamber A of the carburetor is a supplemental cylindrical casing M of very much 90 smaller diameter. This chamber is preferably formed open at its bottom and provided with a closing, but removable, screw plug s thereat. It has a closing top wall t provided with an upstanding hub t². It is made near, 95 but at a sufficient distance above its bottom with a horizontal partition u dividing the casing M into upper and lower chambers v and w. The passage w² of small diameter connects the liquid chamber in the carburetor body A with the lower chamber w in the supplemental casing. The upstanding jet tube or nipple x is screw engaged through and upstanding above the partition u and forms communication from the lower chamber w to the upper chamber v. Suitably above the partition are one or more air intake ports v²; and quite near the top of the 100 casing are one or more air intake ports v³. The needle valve P screw engages through the hub provided top wall t and coacts with 105 the mouth portion of the jet tube x.

The centrally apertured cup shaped cap y is fitted about the aforementioned upstanding hub t², and has its depending annular 110 flange-like and casing-encircling portion provided with one or more apertures y³ for more or less opening and fully closing the air intake openings v³. The nut z screws on the upstanding hub t² and holds in place and 115 also tensions the cup shaped shutter y.

From the intermediate part of the upper chamber v in the supplemental casing M, a pipe has communication, which pipe also extends to and connects into the engine connection member C.

120 The apparatus is seen to be one comprising a main carburetor and a supplemental carburetor.

Both departments of the carburetor may 130

operate conjointly under any positioning or adjustment for regulation respectively thereof; and when the main carbureter is entirely throttled, the engine may be run 5 at moderate or comparatively slow speed on the gas intake and independently of the main carbureter; and under any proper adjustment of the supplemental carbureter, the engine is prevented from becoming stalled 10 from throttling down of the main carbureter.

I claim:

1. In a carbureter, the main inclosed liquid chamber and a central vertical chamber therewithin, having a lateral tubular extension for connection with the engine, and having a lateral opening provided with an apertured end wall, a passage connecting the chambers, and a movably carried needle 15 valve for controlling said passage, a circular cap member for closing the top of the said central chamber and revolvably movable relatively thereto and having an outwardly extended flange provided with gear teeth, a 20 revolvably movable shutter having valve apertures in its front, adapted to have open and closed relations to the apertures in the end wall of said opening, and comprising an annular flange having gear teeth at its 25 edge portion in mesh with the teeth of said cap, means for revolvably moving the cap and therewith the shutter, and means actuated by the revolvble cap for proportionately moving the needle valve.
2. In a carbureter, the main inclosed liquid chamber and a central vertical chamber therewithin, formed with an open top, and lateral openings, one having a tubular extension for connection with the engine, and 40 the other having a hollow hub provided with an apertured end wall, and said central chamber having therewithin a vertical upwardly open tubular jet, the lower portion of which is in connection with the main chamber, a circular cap member for closing the top of the said central chamber and revolvably movable relatively thereto and having an outwardly extended flange edgewise provided with teeth, means for revolvably moving 45 said cap, a cup shaped shutter having valve apertures in its front, adapted to have open and closed relations to the said apertures of the hub end wall, and having its cylindrical flange-like portion surrounding the hub provided at its edge with teeth in mesh with the teeth of said cap flange, a needle valve for opening and closing said jet tube, and means actuated by the revolvble cap means for raising and lowering the 50 needle valve proportionately with the movement of the apertured shutter.
3. In a carbureter, a main inclosing liquid chamber and a central vertical chamber therewithin having a lateral tubular extension for connection with the engine, having 55

a lateral opening provided with an apertured end wall, and having a passage connecting said chambers, and the central chamber having an axially vertical hub supported centrally therewithin, a cap for closing the top of the central chamber and revolvably movable relatively thereto and provided thereon with concentric opposed arc shaped cams, a block having laterally extending members in impingement on said cams, and provided with a depending sleeve extending and slidably engaged within the said axially vertical hub and means for preventing rotation of the sleeve relatively to the hub, a spring for imparting a downward force to said sleeve, a needle valve screw engaged through said sleeve and extended to a controlling relation to the said passage connecting said chambers, means for imparting revolvble movements to said cap and the cams carried thereby, a shutter for opening and closing the apertures in the wall of the lateral opening of the central chamber, and means actuated by the cap for conjointly operating said shutter.

4. In a carbureter, a main inclosing liquid chamber and a central vertical chamber therewithin having a lateral tubular extension for connection with the engine having a lateral opening provided with an apertured outer wall, and having a passage connecting said chambers, and the central chamber having an axially vertical tubular hub centrally therewithin, provided with a spline way, a cap for closing the top of the central chamber and revolvably movable relatively thereto and provided with concentric opposed arc shaped cams thereon, a block, having opposite laterally extending members in impingement on said cams, and provided with a depending sleeve extending and slidably engaged within the said axially vertical hub, having a rib engaged in said spline way, and formed with a shoulder above the hub, a split bushing screw engaged through the top of the cap and forming a slide bearing for the sleeve, a spring in compression between the split bushing and the shoulder of said sleeve, a needle valve screw engaged through said block and sleeve and extended to a controlling relation to the said passage connecting said chambers, means for imparting revolvble movements to said cap and the cams carried thereby, a shutter for opening and closing the apertures in the lateral opening of said casting and means actuated by the cap for conjointly operating said shutter.

5. In a carbureter, a main inclosing liquid chamber and a central vertical chamber therewithin having a lateral tubular extension for connection with the engine, having a lateral opening provided with an apertured end wall, and having a passage connecting said chambers, and the central cham-

ber having an axially vertical hub supported centrally therewithin, a cap for closing the top of the central chamber and revolvably movable relatively thereto and provided thereon with concentric opposed arc shaped inclined cam plates, each having its low end fastened to the cap and having an adjusting screw engaged through its high end and bearing on the top of the cap, a block having laterally extending members in impingement on said cam plates, and provided with a depending sleeve extending and slidably engaged within the said axially vertical hub and means for preventing rotation of the sleeve relatively to the hub, a spring for imparting a downward force to said sleeve, a needle valve screw engaged through said block and sleeve and extended to a controlling relation to the said passage connecting said chambers, means for imparting revolute movements to said cap and the cams carried thereby, a shutter for opening and closing the apertures in the wall of the lateral opening of the central chamber, and means actuated by the cap for operating said shutter conjointly therewith.

6. A carbureter, comprising a main liquid chamber and a chamber having passaged connection from the liquid chamber thereto, and a needle valve for regulating said passaged connection, regulated means for the admission of air into said second chamber, and a conduit extended from communication with the second chamber for connection with the engine, and a supplemental chambered casing adjacent the main liquid chamber, supported thereby, having a chamber dividing partition near its bottom, having a transverse passage leading to the lower chamber thereof from the main liquid chamber, having a jet tube upstanding above said partition concentrically within the supplemental casing, having an air intake opening through its side below the top of the jet tube, and having an air intake opening in the upper portion thereof, a shutter for regulating the opening and closing of the latter opening, a needle valve for opening and closing the jet tube, and a pipe leading from intermediately of the height of said supplemental casing to connection with the said engine connection conduit.

7. A carbureter, comprising a main liquid chamber, a mixing chamber therewithin, means for regulating the entrance of liquid fuel and air into the mixing chamber, and a conduit extended from communication with the mixing chamber for connection with the engine, and a supplemental chambered casing adjacent the main liquid chamber, supported thereby, having a chamber dividing

partition above its bottom, having a transverse passage leading to the lower chamber therein from the main liquid chamber, having a jet tube upstanding concentrically within the supplemental casing above the passage leading to the lower portion thereof, having an air intake opening through its side below the top of the jet tube, and having an air intake opening through its side at the upper portion thereof, a cup shaped cap and shutter rotatively fitted about the top of the supplemental chamber for regulating the opening and closing of the latter named opening therein, a needle valve screw engaged through said cap for opening and closing the jet tube, and a pipe leading from intermediately of the height of said supplemental casing to connection with the said engine connection conduit.

8. A carbureter, comprising a main liquid chamber, a mixing chamber therewithin, means for regulating the entrance of liquid fuel and air into the mixing chamber, and a conduit extended from communication with the mixing chamber for connection with the engine, and a supplemental cylindrical casing adjacent the main liquid chamber, supported thereby, constructed open at its bottom, and having a closing top wall provided with an upstanding hub, having a transverse passage leading into the lower portion thereof from the main liquid chamber, and having a chamber-dividing partition in its lower portion, but above said passage, a jet tube open at top and bottom, screw engaged through said partition and upstanding concentrically within the supplemental casing above the partition, and said casing having an air intake opening through its side below the top of the jet tube, and having an air intake opening through its side in the upper portion thereof, a centrally apertured cap fitted about the said upstanding hub and having its depending annular flange apertured and for opening and closing the upper opening of the supplemental casing, a nut screwing on the hub above, and engaging, the said cap, a needle valve screw-engaged through the hub provided top wall and coacting with said jet tube, a screw plug for removably closing the bottom of the casing, and a pipe leading from the chamber in said casing above the partition to connection with the engine connection conduit.
